UNITED STATES PATENT OFFICE.

FRED EVANS, OF SUMMIT, NEW JERSEY, ASSIGNOR, BY MESNE ASSIGNMENTS, TO
VOICES INCORPORATED, A CORPORATION OF DELAWARE.

VOICE MECHANISM.

Application filed November 23, 1922. Serial No. 602,705.

My invention relates to improvements in voice mechanisms and more particularly to mechanisms adapted to emit sounds such as "ma-ma" or "pa-pa," etc. The main object 5 of the invention is to provide an arrangement which will more or less automatically produce such sounds and which mechanism is simple and efficient in operation and construction and one which is not likely to get 10 out of order.

Further and more specific objects, features and advantages will more clearly appear from the detail description given below taken in connection with the accompanying drawings which form part of this specification.

In the drawings Fig. 1 is a perspective showing a cradle with a voice mechanism carried thereby embodying my improvements in one form. Fig. 2 is a vertical section of 20 the voice mechanism shown in Fig. 1. Fig. 3 is a vertical section through a voice mechanism embodying my improvements in a modified form. Fig. 4 is a vertical section of the same taken at right angles to the section 25 shown in Fig. 3. Fig. 5 is a transverse section taken on the line 5—5 of Fig. 4.

Referring to Figs. 1 and 2, 6 represents a cradle provided with suitable rocking supports 7, 7. The cradle is provided in one 30 end with a compartment 8 across which extends a rod 9 rigidly fixed to the sides 10, 10 of the cradle. Rigidly secured to the rod 9 as by set screw 11 is a head member 12 provided with a suitable reed pipe 13 having a 35 reed 14. The reed pipe 13 extends to a passageway 15 in the head 12, passageway 15 opening to the outside atmosphere at 16. 17 represents another head member which is heavily weighted as by being made of lead 40 and adapted to slide by gravity along rod 9. The members 12 and 17 are connected by flexible means 18 such as a flexible membrane of rubberized cloth so as to provide a bellows. The head members 12 and 17 are preferably in the shape of circular disks and the 45 flexible means 18 of general cylindrical shape so that the bellows takes the form of a cylindrical bellows. The head 12 is provided with a leakage hole 18. 19 represents a 50 valve member having one end secured to the head 17 at 20. The valve member 19 is preferably made of a thin flat strip of metal. The valve member 19 is adapted to slide through suitable apertures in the extension 55 21 of the head 12 and cross the passageway

15 so as to open and close the same to the outside atmosphere. For this purpose the valve 19 is provided with two apertures 22 and 23, the former being relatively short and the latter relatively long.

When the cradle is rocked over to the right as viewed in Fig. 1, the weighted end member 17 will slide along the bar 9 to the right putting the air in the bellows under pressure and when the aperture 22 comes opposite the passageway 15, the reed 14 will speak uttering a short sound like "ma," and as the member 17 continues its travel to the right, the aperture 23 will soon come opposite the passageway 15 causing the reed to again speak and utter another but longer sound like "ma." When the member 17 thus slides toward the rigid member 18, the air in the bellows is compressed and forced out through the reed pipe 13 with sufficient force to cause the reed to make the sounds in question when the apertures 22 and 23 come opposite the passageway 15 as above described. The leakage hole 18 is of just sufficient size to permit enough air to leak in and out so that the member 17 will move by gravity when the apertures 22 and 23 are not opposite to the passageway 15. When the cradle is rocked back to the left as viewed in Fig. 1, the weighted head 17 will be thrown to its normal position as shown in Figs. 1 and 2. It will thus be seen that the valve 19 is adapted to successively open the reed pipe to the outside atmosphere upon a single movement of the head members toward one another, and the whole operation takes place substantially automatically by gravity actuating the weighted member 17. Since the member 17 slides on the rod 9, the two head members are movable relatively toward one another in successively parallel planes.

Referring to Figs. 3, 4 and 5, in the modification there shown, 25 represents a suitable cylindrical container made out of cardboard or other suitable material having fixed thereto in a head 26 by means of screws 27. 28 represents a reed pipe carried by the head 26 and having operatively related thereto a reed 29. Reed pipe 28 opens into a passageway 30 in the head 26, the outer end of which passage 30 is adapted to be opened or closed to the outside atmosphere by means of a flat metal sliding valve 31. The upper end of the sliding valve 31 is rigidly fixed to a weighted head 32. The head members 26

and 32 are circular in shape and connected by means of a flexible membrane 33 so as to form a bellows of general cylindrical shape. The valve member 31 extends from the head 32 down through the bellows and slides through the head 26 opposite the end of passageway 30 and is provided with two openings 34 and 35, the latter being relatively long as compared with the former. The lower end of the cylindrical container 25 is closed by perforated head 36 through which the lower end of the valve member 31 slides.

The apparatus is adapted to be placed inside the trunk portion of a doll. When the doll is seated the valve member 31 is pushed upwardly carrying with it the weighted head 32 so that the parts assume the position shown in Figs. 3 and 4. When the doll is lifted the weight 32 drops by gravity carrying with it the valve member 31 and compressing the air in the bellows and when the aperture 34 comes opposite the passageway 30, air is forced out through the reed pipe causing the reed to speak and emit sound like "ma" and as the head 32 continues to be forced downward under the weight of head 32, the aperture 35 comes opposite the passageway 30 and causes the reed to again speak and utter the sound "ma" but of longer duration. The sounds thus emitted are carried to the outside atmosphere through the perforations in head 36.

It will be apparent from the above that the arrangements shown are extremely simple and efficient in operation and construction and the parts are compactly arranged. The valve member is secured to one end of the bellows and slides with respect to the other so that the apparatus is not likely to get out of order.

Although I have described my improvements in great detail and with respect to preferred forms thereof I do not desire to be limited to such details or forms since many changes and modifications may be made and the invention embodied in widely different forms without departing from the spirit and scope thereof in its broader aspects.

What I claim as new and desire to secure by Letters Patent is:

1. A sound device having in combination a cylindrical casing, a head fixed therein, a

weighty head movable by gravity therein to form a compressible air chamber between said heads, a reed pipe carried by the fixed head, an opening through which the sound issues from the reed pipe, and a control member secured to said weighty movable head and movable therewith and having a plurality of apertures therethrough adapted to move past said opening to control the issuance of sound from the reed pipe. 55

2. A sound device having a fixed head, a weighty head movable by gravity toward and from the fixed head, a bellows connected between said heads, a sound reed carried by the fixed head and operated by the bellows, an opening through which the sound from the reed is adapted to issue, and a control member secured to said weighty movable head and movable therewith and having a plurality of apertures therethrough adapted to move past said opening to control the issuance of sound from the reed pipe. 60

3. A sound device having in combination a cylindrical casing, a head fixed therein, a weighty head movable by gravity therein to form a compressible air chamber between said heads, a reed pipe carried by the fixed head, an opening through which the sound issues from the reed pipe, and a control member secured to said weighty movable head and movable therewith and having a plurality of apertures therethrough adapted to move past said opening to control the issuance of sound from the reed pipe, and said control member comprising a flat strip passing through the compressible air chamber. 70

4. A sound device having a fixed head, a weighty head movable by gravity toward and from the fixed head, a bellows connected between said heads, a sound reed carried by the fixed head and operated by the bellows, and opening through which the sound from the reed is adapted to issue, and a control member secured to said weighty movable head and movable therewith and having a plurality of apertures therethrough adapted to move past said opening to control the issuance of sound from the reed pipe, and said control member passing through the bellows. 95

In testimony whereof I have signed my name to this specification.

FRED EVANS.
